[57] CLAIM

The ornamental design for a computer housing, as shown and described.

DESCRIPTION

FIG. 1 is a front side perspective view of a computer housing showing my new design;

FIG. 2 is a front elevational view thereof;

FIG. 3 is a side elevational view thereof;

FIG. 4 is a rear elevational view thereof;

FIG. 5 is a top plan view thereof;

FIG. 6 is a side elevational view thereof opposite that shown in FIG. 1;

FIG. 7 is a bottom plan view thereof.

FIGS. 2-7 are shown on a reduced scale.
